CLAIM

The ornamental design for a double vent for a soffit panel, as shown and described.

DESCRIPTION

FIG. 1 is an isometric view of a double vent for a soffit panel according to an exemplary embodiment.

FIG. 2 is a bottom plan view of the double vent for a soffit panel shown in FIG. 1;

FIG. 3 is a top plan view of the double vent for a soffit panel shown in FIG. 1;

FIG. 4 is a bottom-end elevation view of the double vent for a soffit panel shown in FIG. 3;

FIG. 5 is a top-end elevation view of the double vent for a soffit panel shown in FIG. 3;

FIG. 6 is a left-side elevation view of the double vent for a soffit panel shown in FIG. 3;

FIG. 7 is a right-side elevation view of the double vent for a soffit panel shown in FIG. 3; and,

FIG. 8 is an enlarged detail of FIG. 7.

Broken lines in the drawings indicate environmental structure or boundaries of the double vent for a soffit panel that form no part of the claimed design.
